UNITED STATES PATENT OFFICE.

JOHN P. WIENS, OF MILWAUKEE, WISCONSIN.

BRUSH.

SPECIFICATION forming part of Letters Patent No. 650,577, dated May 29, 1900.

Application filed December 20, 1899. Serial No. 740,979. (No model.)

To all whom it may concern:

Be it known that I, JOHN P. WIENS, a citizen of the United States, and a resident of Milwaukee, in the county of Milwaukee and 5 State of Wisconsin, have invented certain new and useful Improvements in Brushes; and I do hereby declare that the following is a full, clear, and exact description thereof.

My invention relates to that class of brushes 10 in which a series of absorbent tufts are bordered by non-absorbent tufts, it being customary to make the absorbent tufts from palma fiber and the non-absorbent tufts from 15 tampo fiber, both of these fibers being material of common knowledge to brush-makers. Manufactures of this kind are commonly known as "dustless" sweeping-brushes and are utilized with a more or less volatile oil, such as kerosene or gasolene, applied to 20 the absorbent tufts in sufficient quantity to saturate the same.

In view of the foregoing my invention has 25 for its object to provide simple economical dustless sweeping-brushes organized to carry a supply of oil and to provide for automatic feed of same in regulated quantity to the absorbent tufts of said brushes, said invention consisting in certain peculiarities of construction and combination of parts hereinafter 30 particularly set forth with reference to the accompanying drawings and subsequently claimed.

Figure 1 of the drawings represents a vertical longitudinal section of one form of my 35 improved brush on the plane indicated by line 11 in the succeeding figure; Fig. 2, a plan view of a reservoir brush-back from which the cover-piece has been separated; and Fig. 3, a vertical transverse section of the brush, 40 this view being indicated by lines 33 in the first figure.

Referring by letter to the drawings, A indicates a back-section having a multiplicity of sockets in which tufts B C are wiredrawn, 45 this operation being common practice in the art of brush-making, and while I show an all-wiredrawn brush it is within the scope of my invention to utilize a brush in which some, if not all, the tufts are otherwise secured in the 50 sockets with which the back is provided, as is also common practice in said art. The tufts B of the brush are of palma fiber or

other suitable absorbent material and the tufts C are of tampo fiber, bristle, or other suitable non-absorbent material.

55

Made fast on the back-section A of the wire-drawn brush herein shown is another back-section D, hollowed out to form upper longitudinal recesses b in opposite directions from its center, and cut in the latter back-section 60 is a channel c, connecting said recesses. For other than an all-wiredrawn brush it is obvious that the back may be in one piece thick enough to provide for the recesses and their connecting-channel.

65

Perforations d in the bottom of the brush-back register with exposed butts of the absorbent tufts B, and whether said back be in sections or one piece, according to demands of the trade, it is provided with a cover E, 70 that is made oil-tight thereon and has a port e, through which oil is introduced to find its way to said tuft-butts when the brush is in working position, a suitable closure for the port being also provided. As herein shown, 75 a flanged nozzle f is made fast in a countersink of the oil-port and provided with a screw-cap g, the latter serving as a closure that may be adjusted to regulate the gravity-flow of the oil to the absorbent tufts of the brush in accordance with the amount of air admitted through said nozzle.

80

The brush-back and its cover E being preferably of wood, said cover is set on with oil-proof cement h, and wherever there is exposure of the wood to oil a coating of like cement is applied to render said wood impervious to said oil.

85

The covered brush-back is provided with a socket for a handle F, and a triangularly-bent wire stay G, connected to said back and the handle, serves as a fender for the brush.

90

In practice the oil supplied to the brush saturates the absorbent tufts of the same to moisten and lay the dust disturbed by said brush during a sweeping operation, and by utilizing a reservoir-back as part of said brush there is automatic feed of said oil, the latter being poured into the reservoir from time to time as may be necessary, the feed being regulated according to conditions under which the aforesaid brush is employed. When not in use, the brush is stood so as to have its tufts uppermost, and the nozzle-cap is screwed

95

100

tight to prevent escape of oil from the reservoir.

Having thus described my invention, what I claim as new, and desire to secure by Letters Patent, is—

- 5 1. A brush comprising absorbent tufts and having a wooden back provided with upper recesses connected by a channel and also provided with bottom passages leading from the recesses to said tufts, a back-cover, oil-proof cement intermediate of the back and cover, similar cement applied to the recessed and channelled interior of said back, an oil-inlet in register with one of the back recesses, and a closure for the inlet.
- 10 2. A brush comprising absorbent tufts and

having a recessed wooden back provided with bottom passages leading from its recessed portion to said tufts, a back-cover, oil-proof cement intermediate of the back and cover, 20 similar cement applied to the recessed portion of said back, an oil-inlet in register with said recessed portion of the aforesaid back, and a closure for the inlet.

In testimony that I claim the foregoing I 25 have hereunto set my hand, at Milwaukee, in the county of Milwaukee and State of Wisconsin, in the presence of two witnesses.

JOHN P. WIENS.
